UNITED STATES PATENT OFFICE

146,346

DESIGN FOR A JEWELRY BOX OR SIMILAR ARTICLE

George F. Brown, Salamanca, N. Y., assignor to Diamond Craft of America, New York, N. Y., a corporation

Application December 5, 1945, Serial No. 124,391

Term of patent 14 years

(Cl. D80—5(6))

To all whom it may concern:

Be it known that I, George F. Brown, a citizen of the United States of America, residing at Salamanca, in the county of Cattaraugus and State of New York, have invented a new, original, and ornamental Design for a Jewelry Box or Similar Article, of which the following is a specification, reference being had to the accompanying drawing, forming a part thereof.

The figure is a perspective view of a jewelry box showing my new design, the cover being illustrated in open position.

The base member is fluted at both ends and at the front but is plain at its rear side. The top of the cover is plain.

I claim:

The ornamental design for a jewelry box or similar article, substantially as shown and described.

GEORGE F. BROWN.
